F. MANKEY.

MOLDING.

No. 16,416.

Patented Dec. 15, 1885

UNITED STATES PATENT OFFICE.

FREDERICK MANKEY, OF WILLIAMSPORT, PENNSYLVANIA.

DESIGN FOR A MOLDING.

SPECIFICATION forming part of Design No. 16,416, dated December 15, 1885.

Application filed November 2, 1885. Serial No. 181,722. Term of patent 7 years.

To all whom it may concern:

Be it known that I, FREDERICK MANKEY, of Williamsport, Lycoming county, Pennsylvania, have invented and produced a new and original Design for Moldings, of which the following is a specification, reference being had to the accompanying photograph, forming part hereof.

My design consists in a new configuration for a molding.

Extending in a longitudinal direction on the surface of the molding is a series of rectangular elevations, A. Between said elevations are grooves or channels B. At each side of said elevations are lateral projections C.

Each projection C shows a rectangular base portion, D, and a trihedral pyramidal portion, E.

The general outline of the edges of the molding shows a series of obtuse-angled serrations alternating with the rectangular recesses.

I claim—

The design for a molding, substantially as herein shown and described, which consists in the rectangular elevations A, the channels B, and the lateral projections C.

FREDERICK MANKEY.
